FLUID-ACTUATED MOTOR ASSEMBLY

Clyde E. Bannister, Houston, Tex., and Willard D. Eakin, Akron, Ohio; said Eakin assignor to said Bannister

Application September 8, 1950, Serial No. 183,806

3 Claims. (Cl. 121—154)

This invention relates to fluid-actuated motors and especially to the valve control of such motors, and is an improvement upon the motor described and claimed in Bannister U. S. Patent No. 2,254,641.

The chief objects of the present invention are to eliminate inertia factors and to eliminate friction factors in the valve control of a motor of the type covered by the above mentioned patent.

More specifically, one of the chief objects is to provide a motor having, for reversing the main valves of the motor, a fluid-actuated auxiliary motor the valves of which, in each half-cycle of operation, will be positively driven by the main motor to such positions as to assure reversal of the auxiliary motor, with the actuation of the auxiliary motor in reverse then further shifting its own valves in the same direction, in the first part of its shifting of the valves of the main motor, so that, upon being initiated by the main motor, the reversal of the valves of the auxiliary motor will be sure to be completed and to be fully maintained until the beginning of the next half-cycle of operation.

A further object is to provide a motor having the mode of operation just described and having the valve ports so arranged that, as to the main motor or the auxiliary motor or both, the outlet port from a given chamber will be closed before the inlet port to the same chamber is opened, to avoid free passage of fluid and consequent reduction of operating pressure.

Another object is to assure full reversal of the exhaust ports of the auxiliary motor, by positive drive of the main motor, before reversal of the inlet ports of the auxiliary motor, the exhaust ports of the auxiliary motor thus being positively reversed by the main motor under full drive setting of the latter's ports.

More broadly stated, my chief objects are to provide an improved fluid-actuated motor having no "dead center" and requiring no reliance upon friction, inertia or an over-center spring for valve reversal.

For purposes of illustration only, the accompanying drawings show the present motor in an assembly inclusive of a well-drilling bit and thus within the scope of Bannister U. S. Reissue Patent No. 19,397, which is a reissue of original Patent No. 1,965,563, granted July 10, 1934, but the present motor is not limited in its utility to the field of well drilling.

Of the accompanying drawings:

Fig. 1 is an axial section on line 1—1 of Figs. 7 and 9, with parts in elevation, of a well drilling assembly showing a motor assembly embodying the invention in its preferred form, with the parts at positions as in Figs. 5, 6 and 9.

Fig. 2 is an elevation of the inlet valve of the auxiliary, valve-controlling motor.

Fig. 3 is an elevation of the main-motor valve member, which is also a part of the auxiliary motor.

Fig. 4 is a fragmentary elevation of the shaft of the main motor, formed with an impeller vane, and showing a part of the main-motor valve member.

Fig. 5 is a fragmentary axial section with parts shown in elevation other than those so shown in Fig. 1, and with the parts in positions as in Figs. 1, 6 and 9.

Fig. 6 is a section on line 6—6 of Figs. 1 and 5, showing the inlet valve of the auxiliary motor in the same position as in Figs. 1, 5, and 9.

Fig. 7 is a section on line 7—7 of Fig. 1.

Fig. 8 is a section at the same height as the sections shown in Figs. 9 to 11, but with the parts shown sym-

2

metrically positioned, as they are during assembly only.

Fig. 9 is a section on line 9—9 of Figs. 1 and 5, with the parts in the same positions as in those figures, with all valve ports of the auxiliary motor closed, certain parts being stopped while others continue to rotate clockwise.

Fig. 10 is a section corresponding to that of Fig. 9, but showing a later stage, with one of the exhaust ports of the auxiliary motor opened and one of its inlet ports about to be opened.

Fig. 11 is a section corresponding to Figs. 9 and 10 but showing a still later stage, at which the valve of the main motor has been forwardly rotated, clockwise, with relation to the main shaft while the latter was rotating clockwise, the valve ports in the main shaft thus being reversed, to start a reverse, counterclockwise, movement of all of the rotatable parts.

Referring first to Fig. 1 of the drawings, the assembly comprises a motor casing 10 the upper end wall of which is provided by a heavy inertia member 11 formed with a central vertical hole 12 to which is coupled a load-sustaining and fluid-conducting hose 13 for lowering and raising the motor assembly in a well hole and for supplying pressure fluid to the motor from the top of the ground.

The assembly comprises a hollow, oscillating, main-motor shaft 14 on the lower end of which is secured a drilling bit 15.

Formed integrally with the main-motor shaft 14 is 30 a vane-type impeller or wing piston 16 which is driven back and forth in a pressure chamber defined by a fluid-abutment member 17 (Figs. 1 and 7), of which the upper end portion is so shaped as to serve as a bulkhead 18 in the motor casing, the floor of said pressure chamber being provided by a lower bulkhead 19. A replaceable lining 20 can be associated with the casing, fluid-abutment member and bulkheads as shown, and replaced by a new one from time to time, to avoid excessive leakage resulting from wear caused by the abrasive material that is present in drilling fluid.

The main-motor shaft 14 is journaled in the two bulkheads, 18, 19, and a two-way thrust bearing 14a is interposed between the main motor shaft 14 and the casing 10.

45 The main-motor shaft 14 is formed (Figs. 4 and 7) with a pair of fluid-inlet ports 21, 22 on opposite sides of and close to the base of its impeller vane 16, at a relatively high position, and, at a lower position, with a pair of fluid-outlet or exhaust ports 23, 24 similarly placed at opposite sides of the base of the impeller vane.

For appropriately controlling flow of fluid through those ports a tubular main-valve member 25, having a dividing wall or partition 26 at a suitable position therein, is rotatably fitted in the hollow main-motor shaft 14 and at its open upper end is journaled in and extends through a central hole in an uppermost bulkhead 27. The bulkhead 27 defines, with the casing 10 and the inertia member 11, a chamber 28 in communication with the hole 12 in the inertia member, the valve member thus being adapted to receive the motive fluid at its open upper end.

For suitable coaction with the ports 21 to 24 in the wall of the hollow main-motor shaft 14 the main-valve member is formed with a main-motor inlet port 29 (Figs. 1, 3 and 7), above the partition 26 and registerable in alternation with the shaft's motor-inlet ports 21, 22, and, below the partition 26, with a pair of main-motor outlet ports 30, 31 so spaced that when the main-valve's motor-inlet port 29 is registered with the shaft's motor-inlet port 22, as in Fig. 7, the main-valve's exhaust port 30 will be registered with the shaft's exhaust port 23 (directly below the port 21 in Fig. 7), and when the main-valve's motor-inlet port 29 is registered with the shaft's motor-inlet port 21, the valve's exhaust port 31 will be registered with the shaft's exhaust port 24 (directly below the port 22 in Fig. 7).

The spacings of these ports are such (Fig. 7) that when the valve is in middle position in its port-reversing movement with relation to the shaft all of the ports are closed. Thus, but only for an instant, fluid is entrapped on both sides of the impeller vane 16, one pair of the shaft's inlet

3

and exhaust ports (22 and 23) being fully closed, and preferably with slight overlap, before the other pair (21 and 24) are opened, so that there is not at any time free flow of motive fluid through the motor, and this avoids lowering of the working pressure of the fluid, for actuating the auxiliary, valve-shifting motor about to be described. The entrapping of the motive fluid on the two sides of the impeller vane is of such infinitesimal duration, or is to such extent relieved by even a slight leakage, that it does not stop the impeller vane too abruptly.

The oscillating movement of the main valve 25 in relation to the main shaft 14 is limited by abutment of the valve's impeller 36 against stop pins 46, 47 projecting upward from the floor of the auxiliary-motor-casing cup 32. This relative movement is of course of such amplitude as to shift the valve 25 back and forth between the position in which it is shown in Fig. 7 and a fully reversed position.

The auxiliary, valve-shifting motor comprises the cup-shaped casing 32 secured upon the upper end of the main-motor shaft 14 as by a set-screw 33 (Fig. 1). This casing is integrally formed with a fluid-abutment 34 and is provided with a lid 35 (Figs. 1 and 5). In the casing 32 is the impeller vane or wing piston 36 of the auxiliary motor, formed integrally with a hub portion 37 of the main valve 25. This hub portion seats upon the upper end of the main shaft 14 (Fig. 1) to sustain the differential of fluid pressures upon the upper and lower faces of the valve's partition 26.

The auxiliary motor casing 32 is in an exhaust chamber 32a defined by the casing 10 and bulkheads 18 and 27, and this chamber is vented by a groove 32b in the inner wall of the casing 10 and extending from the chamber to the lower end of the casing.

The hub portion 37 of the main-valve 25 is formed with two arcuately large motor-inlet ports 38, 39 at opposite sides of its impeller vane 36, each at a considerable distance from the base of the vane. The auxiliary casing 32 is formed with two arcuately large exhaust ports 40, 41, preferably at opposite sides of the casing.

For opening and closing the motor-inlet ports 38, 39 a tubular pilot valve 42 is rotatably fitted in the upper end of the main valve 25 and at its upper end is formed with a laterally projecting stop-wing 43, adapted to be stopped in each half-cycle of oscillation by one or the other of stop pins 43a, 43b (Figs. 1, 5 and 6) projecting upward from the stationary bulkhead 27.

For opening and closing the exhaust ports 40, 41, a sleeve valve 44 is rotatably fitted on the casing and is formed with an outwardly projecting stop-wing 45, adapted to be stopped in each half-cycle of oscillation by one or the other of stop pins 45a, 45b projecting upward from the stationary bulkhead 18.

In the present embodiment the size and spacing of the set of valve ports and the stop wings are in accord with the positioning of the stop pins 45a and 43a in radial alignment with the center of the motor, as shown, and likewise the stop pins 45b and 43b, and this seems desirable for simplicity of layout, but is not essential.

For opening into one and then the other, in alternation, of the main valve's motor-inlet ports 38, 39, while keeping the other one closed, the pilot valve 42 is forward with a port 48 the arcuate length of which not necessarily but preferably is substantially less than the arcuate distance between the ports 38, 39 in the hub 37 of the main valve, for reasons hereinafter stated.

For opening one and then the other, in alternation, of the auxiliary-motor exhaust ports 40, 41, while keeping the other one closed, the sleeve valve 44 is formed with two arcuately large ports 49, 50, preferably but not necessarily so spaced in relation to the ports 46, 41 of the auxiliary-motor-casing cup 32 that when the cup and the sleeve valve are in the relative positions in which they are shown in Figs. 8 and 9 both of the cup's ports 40, 41 will be closed.

The mode of operation of the main motor, with appropriate shifting of the main valve 25-37, is well understood in the art and will be clear from the foregoing description and inspection of Figs. 1, 3, 4 and 7.

The operation of the auxiliary motor to provide such shifting of the main valve 25-37 (Fig. 3) is as follows:

In the original assembling of the parts, it is necessary only that the parts of the auxiliary motor be left in a relationship other than their non-flow, symmetrical, relationship of Fig. 8.

4

Assuming that this is done by moving the valve-impeller vane 36 into contact with its left-hand stop pin 46, this will put the main motor ports in the positions represented by Fig. 7 and passing of motive fluid into the assembly through the hose 13 will drive clockwise the main impeller 16, main shaft 14, the auxiliary-casing cup 32 secured to the main shaft, the main-valve impeller 36, by positive drive of its stop pin 46, the main valve 25-37 and, with it, by friction, the pilot valve 42.

This positive clockwise drive of the cup 32 and the valve impeller 36 will bring the stop-wings 43, 45 into contact with the respective stop pins 43b, 45b and at a certain stage of clockwise rotation the parts will be in the relationship in which they are shown in Fig. 9 (and in Figs. 1, 5 and 6), with all ports of the auxiliary motor closed.

The main-motor ports still being in full-drive relationship, the main shaft 14, cup 32, pin 46, impeller 36, and main valve 25-37 will continue to rotate clockwise, while the pilot valve 42 and valve sleeve 44 are held by their stop pins 43b, 45b, the parts thus being brought into the relationship in which they are shown in Fig. 10, with the auxiliary-motor exhaust port 40 well opened to the sleeve valve's port 49 but with the auxiliary-motor inlet port 38 well past its fully closed position and with the other inlet port, 39, just ready to open to the pilot valve 48.

Further driving of the main shaft and positive driving of the main-valve impeller 36 by the pin 46 opens the said port 39 to the said port 48, admitting motive fluid to the exhaust-closed chamber behind the valve impeller 36 and, with only a frictional load to be overcome (friction of the main valve in the main shaft) quickly jumps the valve-impeller vane 36 forward, in the direction of general rotation, from its stop pin 46 to its stop pin 47, which quickly and fully reverses the main-motor ports, the auxiliary motor parts then being as shown in Fig. 11.

When the opening of the port 39 to the port 48 is once begun, as it is sure to be by the positive drive of the pin 46, it is positively continued until the port 39 is so far opened that the vane 36 starts its forward jump, leaving the pin 46, and when its forward jump is started it is sure to be continued and completed, and at increasing speed, because its forward movement, of itself, further overlaps the port 39 upon the port 48.

If the main shaft 14, cup 32, main-valve vane 36 and main valve 25-37 are not stopped by contact of the main-shaft impeller vane with the ends of its chamber, which are the faces of the fluid-abutment 34, Figs. 8 to 11, or adjustable stops (not shown) that may be mounted upon it, such parts continue to rotate until reversed by the fluid pressure of main-valve reversal, at or near the positions in which they are shown in Fig. 11. In that figure, representing such fluid-pressure reversal of the main shaft, etc., a re-closing of the auxiliary-motor inlet ports 39, 48 is shown as having begun, but this is made permissible by the long arcuate length of all of the auxiliary-motor ports, by reason of which the ports 39, 48, in their positions of Fig. 11, still have ample flow capacity.

The amplitude of oscillation of the main shaft 14 can be changed by simply changing the positions of the stops 43a, 43b, 45a, 45b.

Upon reversal of the main-motor ports the reverse half-cycle of oscillation is of course begun and it, ending with the next reversal, of course corresponds to the clockwise movement and reversal just described.

As friction between the main shaft and the main valve within it is overcome by the dominant pressure of the motive fluid, which, with the stop pins 46, 47, positively controls the main-motor ports at all times, the main valve can be snugly fitted in the main shaft for avoidance of leakage, and the only reliance upon friction for driving is for rotation of the pilot-valve 42 with the main valve 25-37 in which it is fitted, and as the pilot valve is light, has no load other than its own inertia opposed to its frictional drive, and it and the main valve start together from non-rotating condition, and only at the speed of the main shaft, with no rebound from a stop, this frictional drive of the light pilot valve can be safely relied upon, especially as the pilot valve can be snugly fitted in the main valve, with the additional advantage of avoidance of leakage, since the friction is sure to be positively overcome at the end of each half-cycle, by the stop pin 43a or 43b.

Having the port 48 of the pilot valve shorter than the

distance between the ports 38, 39 is a convenient one of the several possible expedients for assuring positive full reversal of the auxiliary-motor exhaust ports and also provides an overlap as security against leakage when the port 48 is closed.

Similarly overlap security against leakage is provided by the relative dimensions of ports and intervening lands shown in Fig. 7, but this is not indispensable. It is permitted by the quickness of the forward jump of the main valve.

Also, even a large amount of inertia slippage of the pilot valve, in the beginning of the reverse movement of the main shaft, etc., would not effect re-closing of the ports 39, 48 (see Fig. 11). Moreover, at that time the main-motor ports already have been fully reversed, and inertia of the comparatively heavy main valve and its vane 36, against its rear stop pin, 47, Fig. 11, is a factor, acting with the pressure differential, for keeping the main valve reversed until the beginning of the next half-cycle.

A large number of different sets of relative dimensions of parts, and size and positioning of ports and of stop-wings and stops is possible without departure from the scope of the invention as defined in the appended claims and without sacrifice of all of the advantages set out in the above statement of objects.

In the appended claims the expression "positive-drive means" is used as meaning driving means throughout which the driving force is transmitted wholly through solid members, as distinguished from transmission of the driving force through a fluid, as in the driving of the member 48 in the above mentioned Bannister Patent No. 2,254,641, after the inner member 52 has been stopped by the pin 56, for initiating the reversal of the auxiliary-motor ports, and thereafter, throughout the following half-cycle.

I claim:

1. A motor assembly comprising a fluid-actuated main motor and a fluid-actuated auxiliary motor for reversing the main motor, each of said motors comprising a fluid-impelled member, a casing therewith defining the two variable volume chambers, and valve means having ports for cyclically charging and venting the said variable-volume chambers, said assembly comprising means for causing the fluid-impelled member of the main motor to move the casing of the auxiliary motor in relation to the casing of the main motor, in opposite directions alternately, the auxiliary motor comprising two spaced apart contact elements in its casing which limit the fluid-actuated movements of the fluid-impelled member therein, said contact elements alternately constituting drive means through which the main motor effects positive-drive of the fluid-impelled member of the auxiliary motor, with the casing thereof, in the first part of each half-cycle of

- operation, a first slide-valve element formed with a port and carried by the fluid-impelled member of the auxiliary motor, a second slide-valve element, frictionally carried by the said first slide-valve element and formed with a port for mating with the said port thereof, spaced-apart stops having fixed relation to the casing of the main motor and limiting the movements of the said second slide-valve element, the main motor's aforesaid positive-drive of the auxiliary motor's fluid-impelled member effecting
- 5 a partial overlapping of the said ports of the said slide-valve elements, by reason of the second slide-valve member being against one of the said stops, to supply pressure fluid to the then rear face of the last mentioned member, and thus initiate forward fluid-impelled movement thereof in relation to the auxiliary-motor casing and the aforesaid contact elements therein, such forward movement of the said fluid-impelled member effecting, by reason of the structure hereinbefore defined, a further overlapping of the said ports upon each other.
- 10 2. A motor assembly as defined in claim 1 and in which the fluid-impelled member of the auxiliary motor is a wing piston and in which the first recited slide-valve element is in fixed relation to the said wing piston.
3. A motor assembly comprising, in combination, a fluid-actuated main motor comprising a reversing fluid-impelled power member and having control ports and valve means for effecting reversals of the settings of said ports, a fluid-actuated auxiliary motor having a reversing fluid-impelled power member for effecting reversals of
- 15 the settings of the valve means of the main motor, said auxiliary motor having control ports and valve means for effecting reversals of the settings of its said ports, reversal initiating means comprising abutment means driven by the said power member of the main motor for initiating
- 20 reversals of the settings of the valve means of the auxiliary motor, and frictional means constituting, at the time the reversal starts, the only means for holding the valve means of the auxiliary motor at each position from which the reversals thereof are initiated, the said ports,
- 25 valve means and fluid-impelled member of the auxiliary motor constituting means for completing each reversal of the setting of the valve means of the auxiliary motor.
